UNITED STATES PATENT OFFICE.

FREDERICK R. SEIDENSTICKER, OF WEST MERIDEN, CONNECTICUT,
ASSIGNOR TO BRADLEY & HUBBARD, OF SAME PLACE.

DESIGN FOR CHANDELIERS.

Specification forming part of Design No. **8,043**, dated February 2, 1875; application filed June 3, 1874.
[Term of Patent 7 years.]

CASE D.

To all whom it may concern:

Be it known that I, FREDERICK R. SEIDENSTICKER, of West Meriden, in the county of New Haven and State of Connecticut, have invented a new Design for Chandelier; and I do hereby declare the following, when taken in connection with the accompanying photographic illustration, to be a full, clear, and exact description of the same, and which said illustration constitutes part of this specification, and represents a front view.

This invention relates to a design for chandelier for supporting lamps; and consists in the peculiar form or configuration of the arms and of the basket to receive the lamp-fount.

This chandelier is intended for two lamps. The arms join at the top, and extend down alike to the right and left. The point of union at the top forms a loop, *a*; thence the arms run down through the upper section, *A*. The inside of the arms is perpendicular, the outside curving outward. Near the lower end of

the upper section the two arms are connected by a cross-bar, *B*, with an ornament, *C*, above, and *D* below. From this connected point the arms curve to the end or lamp-rest, *E*, the upper side plain. Upon the under side the arm is straight at three points, *b d e*, and between the said straight portions the curve is the reverse of the upper side. The said straight portions are each finished with an ornament, all as shown.

I claim—

The design for chandelier consisting of two arms uniting at the top to form the loop *a*, thence running to the lamp-rest *E* in two outward curves, and the inner or under side of the arms formed in straight sections *A e d b*, with intermediate curves, and connecting-bar *B*, as shown and described.

FREDERICK R. SEIDENSTICKER.
